PORTABLE TOOL WITH SWIVEL HEAD

Filed Oct. 23, 1944

UNITED STATES PATENT OFFICE

2,496,027

PORTABLE TOOL WITH SWIVEL HEAD

Maurice Trapet, Los Angeles, Calif.

Application October 23, 1944, Serial No. 559,959

12 Claims. (Cl. 121—36)

1

This invention relates to improvements in portable tools, and has for its principal object the provision of a basic hand tool structure of extremely simple design adapted to control the flow of air, gas, fluids, compounds, or the like while under pressure, from a source of supply to and through the operating head of the device, which may be adapted for use as an air blower, a rotor, a vibrating tool, a dispensing nozzle, or any other purpose to which the principles involved may be applicable.

A further important object of the invention is to supply a device of the above character having a dispensing or operating head which can be swung at an angle to the longitudinal axis of its handle portion without loosening or detaching any of the parts or otherwise necessitating substantial time-consuming effort, so that the working portion thereof may be directed at locations heretofore considered inaccessible to devices of the same general character, resulting in greater convenience, substantial saving of operating time, and more satisfactory and efficient performance in executing work operations, thus also considerably expediting production in such uses as involve manufacturing or construction.

A still further object of the invention is to provide a portable combination tool adaptable for dispensing or utilizing elements such as air, gases, fluids, compounds, or the like under pressure, as, for example, use of such compressed elements for actuating vibrating or rotating mechanisms contained in the tool's working portion or head, in which the working or exhaust portion is conveniently movable at an angle to its base for the purpose of reaching concealed or out-of-the-way places, or for multiple operations heretofore requiring the use of two or more separate tools, or separate working heads interchangeable in connection with a common handle or base.

Another and still further object of the invention is to provide, in a pneumatic or hydraulic type of portable tool having a pivoting dispensing or working head indexed for locating certain operating positions, an improved and extremely simple and novel valve mechanism which effectively controls the flow of the actuating element thereof, and at the same time automatically locks the tool's indexing mechanism in any given working position while an actuating element is flowing through the device, whereby a rigid, non-shifting, non-rattling relationship is maintained between the major component parts of the device, thus guarding against damage to the tool and possible

2

injury to the operator, and rendering the device fool-proof.

Other and further objects of the invention will be apparent from the disclosure in the accompanying drawing and following specification.

The invention, in a preferred form, is illustrated in the drawing and hereinafter more fully described.

In the drawing:

Figure 1 is a central longitudinal section through an air-hammer embodying the invention, showing its pivotally mounted head in one of several possible operating positions, and indicating another of its operating positions in broken lines.

Figure 2 is a sectional view through the operating head of the device, taken on the line 2—2 of Fig. 1.

Figure 3 is a transverse sectional view through the main body or handle portion of the device, taken along the line 3—3 of Fig. 1.

Figure 4 is another transverse sectional view through the main body or handle portion of the device, taken on the line 4—4 of Fig. 1.

Figure 5 is still another transverse sectional view through the handle portion of the device, taken along the line 5—5 of Fig. 1.

As shown in the drawing.

The elongated main body portion of the tool 10 is in the general shape of a handle 10 provided at its forward end with an integral extension 11 preferably inclining 45 degrees, which extension is transversely bored through at right angles to its own longitudinal plane to form a cone-shaped circular socket or bearing 12 tapering uniformly downward and ending in a reduced lower orifice 13.

An operating head 14 is removably and rotatably mounted at the working end of the handle 10 by means of the head's integral rounded tapering shank 15, which is of a shape corresponding to the inner contour of the socket 12 and is fitted therein so as to render the head 14 freely rotatable. A reduced circular concentric projection or boss 16 integral with the shank 15 is exposed exteriorly of the orifice 13 and is fitted with a retaining ring or similar stop element 17 connected to the boss 16 by means of a laterally disposed pin 18 extending through both the elements 16 and 17, thus securing the head 14 to the base 10. An expansion washer or similar spring-like element 19 is interposed between the parts 11 and 17 to provide the desired tension.

The rotatable head 14 is adapted to carry any suitable form of contact element or discharge

mechanism, such as, for example, the compressed air actuated hammer assembly illustrated in Fig. 1, which comprises a piston-like hammer element 20 operably mounted for longitudinally slidable movement within its cylindrical housing 21, which is preferably set obliquely into the head 14 by threadable insertion into a correspondingly directed bore 22 having a relatively wide centrally disposed annular air-chamber 23 the surrounding sidewall of which is spaced away from the element 21 so as to form an air-jacket about the latter.

A reduced annular concentric depression or socket 24 at the bottom of said bore is adapted to form a seat for the lower end of the tubular element 21 for the purpose of its rigid alignment and also to form an air-tight seal or cap for the cylinder's lower end at this point.

The piston 20 is preferably of the shape best illustrated in Figures 1 and 2, wherein its narrow work-contacting end is adapted to snugly extend in slidable relationship through the relatively narrow exterior orifice 25 formed centrally of the cylinder's exposed portion 26.

The interior of the cylinder 21 is formed with a narrow upper chamber or bore 27, the annular sidewall of which is peripherally drilled at a point exteriorly of the head 14 to provide laterally directed exhaust of discharge ports 28 leading from the interior of the cylinder 21 to the outer atmosphere through an annular tapering deflecting vent 29 formed by a suitably flanged ring 30 threadably mounted upon the outwardly projecting portion 26 of the cylinder at a point between the lateral discharge ports 28 and the head 14, for the purpose of directing any air or the like expelled from the device in the desired direction so that the expelled element may be utilized for blowing away dust, dirt, chips, or the like which may accumulate during a working operation, or for other practical purposes.

The lower bore 31 of the cylinder's interior is substantially wider than the upper bore 27, and its sidewall area is also peripherally drilled adjacent its upper terminus to provide laterally directed entry ports 32 leading from the annular air passage 23 to the interior of the cylinder 21 for the introduction of compressed air or other actuating elements adapted to flow through the cylinder and its contained piston 20 so as to cause the desired vibrating motion of the latter as hereinafter described.

The body of the piston 20 is preferably formed with a series of suitably spaced relatively wide annular cylinder-contacting surfaces 33, 34, 35, and an intermediate neck portion 36 of substantially reduced diameter which is laterally drilled to provide air passages 37 leading from the surrounding annular chamber-like area within the cylinder 21, to a longitudinally disposed central bore 38 communicating with the interior of the cylinder at a point directly below or behind the piston 20, where an air chamber 39 is formed whenever the piston 20 is in suspended position.

The handle 10 is accordingly adapted for conducting compressed air or some other pressure element from a source of supply to the interior of the operating head 14, and is therefore provided with a hose connection or the like 40 attachable to a supply nozzle (not shown). A series of communicating passages 41, 42, 43, 44, 45, 46, 47, 48 form a continuous conducting line through the interior of the handle 10 and through certain of the handle's contained parts, such line extending from the open connection 40 to the forward feeder channel 49.

The feeder channel 49 is adapted to feed the compressed air or other pressure element into the operating head 14 while the latter is in any predetermined operating position, such as either of the two positions indicated in Figure 1. For this purpose a two-way connecting passage 50 is laterally drilled through the head's shank 15, one of the oppositely disposed end openings of which passage comes into registration with the air feed channel 49 whenever the head 14 is turned to one of the said operating positions. A centrally disposed longitudinally directed air passage 51 leads from the two-way air passage 50 into the annular jacket 23. It will be apparent that while one orifice of the lateral passage 50 is in communication with the feeder channel 49 its opposite orifice will be blocked by the adjacent inner surface of the socket 12, as best shown in Fig. 1.

The twin parallel channels 46, 47 of the aforesaid air-circulating system are positioned within the oppositely disposed side portions of a removable insert or guide element 52, the forward end 53 of which is provided with a transverse slot 54 in which a trigger-cam 55 is suitably positioned so as to be rotatable upon a pin 56. Air-tight connections between certain of the removable elements within the handle 10 are assured by the interpositioning of suitably shaped gaskets or the like 57, 58.

The flow control mechanism contained within the handle 10 preferably includes a manually operated ball-shaped check valve 59 centrally disposed within the passage 43 and normally held in closed position against the annular seat 60 by a small coil spring 61, the seat 60 being spaced away from the adjacent elements 52, 53 so as to form the air-deflecting passage 45 leading from the passage 44 to the twin parallel channels 46, 47, from which channels the air is directed into the feed channel 49 via the V-shaped passage 48, which is best illustrated in Figures 1 and 4.

The elongated guide element 52 is removably positioned forward of the connection 40 and is prevented from rotating within the handle 10 by a vertically disposed pin or plug 62 co-operating with the adjacent slot 63 of the member 52. The guide element 52 has a central longitudinal bore 64 within which is slidably positioned a plunger or the like 65 adapted to contact one end of a coil spring 66 abutting a stop element 67, the spring 66 being adapted to normally hold the plunger's forward projecting end 68 in contact with the adjacent trigger-cam's arcuate edge 69.

The plunger 65 has an integral rearwardly directed longitudinal extension or stem 70 of reduced diameter extending centrally through the spring 66 and stop element 67 as well as through the annular guide ring or plug 71 which serves as an air pressure seal to prevent escape of the air or other actuating element flowing through the chamber 45 while being diverted from the incoming passage 44 to the twin parallel channels 46, 47.

The stem 70 projects rearwardly through the passage 45 and into the valve seat's central orifice 44, where its terminus is in close proximity to the seated ball 59 so as to be in position to instantly dislodge the latter upon slightest rearward movement of the plunger 65.

The bottom of the trigger-cam 55 has an integral downwardly extending projection 72 depending into an adjacent handle slot 73, at which point it engages the upper surface of a button element or similar manual control 74 which is pivoted at 75, partially recessed within the slot 73, and restricted in its outward movement by a rearwardly

disposed extension 76 adapted to contact a stop shoulder 77 integral with the body 10. It will be seen that pressure upon the button 74 will cause the rising arcuate cam edge 69 to bear against the adjacent terminus 68 of the plunger 65 and result in unseating of the ball valve 59.

A "snap-in" system of indexing is provided for the purpose of automatically interrupting rotation of the swivel head 14 at certain predetermined working positions to bring about a perfectly aligned operating relationship between the head 14 and the handle 10 without necessitating any extra examination and adjustment, regardless of the particular working angle of the head's contained apparatus in relation to the handle 10.

This indexing system consists of a plurality of spaced notches or depressions 78, 79, positioned along the periphery of the shank 15, which notches are adapted to be entered or engaged by the tapering end 80 of a slidable spring-pressed pin 81 positioned within a longitudinal bore 82 located in the forward end of the handle 10, the path of travel of said pin 81 being restricted by means of its longitudinal slot 83 which is movable over and adapted to co-operate with a stationary laterally disposed stop pin 84.

A coil spring 85 for actuating the longitudinally slidable indexing pin 81 is slidably positioned between the latter and a second elongated pin element 86 of similar diameter and similarly slidable within the bore 82, the element 86 extending rearwardly and having one end 87 projecting into the cam-containing compartment or slot 54, the adjacent pivotally mounted trigger-cam 55 having a forwardly directed upper protuberance 88 held in constant spring-pressed contact with the pin end 87 by reason of the blocking or bracing contact between the button 74 and the cam's lower projection 72, while the expansion spring 85 constantly urges the other pin element 81 forward but nevertheless readily yieldable to any back-pressure created against its projecting forward end 80 as said point rides smoothly and easily out of the notches 78 and 79 when the operator turns the head 14 from one indexed position to another, as between operating periods.

However, it will be apparent that when the tool is properly indexed and fully operative in either working position and supplied with compressed air or other actuating force for its work contact means, slight pressure against the exposed outer edge 89 of the control button 74 will rotate the trigger-cam 55, and such action will at one and the same time cause the cam's arcuate edge 69 to bear against the projecting end 68 of the plunger 65 to instantly open the valve 59 and will also simultaneously cause the trigger-cam's forward projection 88 to bear against and throw the adjacent pin element 86 forward to tightly compress the spring 85 against the indexing pin 81, resulting in temporary locked engagement of the latter's tapering point 80 within one of the notches 78 or 79 and thereby maintaining a positive and rigid alignment of the major parts 10 and 14 during the entire time the device is in operation, preventing vibration or jarring therebetween which might otherwise cause accidental rotation of the head 14 and consequent damage to the device and possible injury to the operator. By centralizing both of the aforesaid movements 70 under the one simple, convenient, and easily manipulated control element 74, the device attains a safe and fool-proof character, since there is no occasion for the operator to overlook troublesome preliminary details of a kind the neglect of which 75

under certain conditions might result disastrously to tool or operator, or both.

It will be obvious that upon introduction of compressed air into the head 14 by way of the system of air passages hereinbefore described, a rapid vibration of the piston 20 longitudinally of its containing cylinder 21 will ensue as air pressure is alternately built up in the air spaces respectively located anteriorly and posteriorly of the piston's widest terminus 35 by the following process: Assuming the starting position of the piston 20 to be as illustrated in Fig. 1 when the valve 59 is opened, compressed air entering the device will course through the continuous system of channels 41, 42, 43, 44, 45, 46—47, 48, 49, 50, 51, 23, 32 and into the cylinder's inner annular space surrounding the piston's enlargement 34, where inward or reverse pressure against the adjacent shoulder of the piston's enlargement 35 will force the piston to recoil until the enlargement 34 is no longer in contact with the upper cylinder wall. This brings the air space surrounding the piston's neck 36 into communication with the inrushing air below the cylinder's dividing shoulder 38, breaking the reverse pressure as the air begins to flow interiorly of the piston by way of the piston's ports 37 and rushes downward through the longitudinal central bore 38 toward and into the posterior pressure chamber 39, thus building up pressure behind the piston's enlargement 35 to force the piston outward. During the piston's outward stroke its enlargement 34 again re-establishes contact with the upper cylinder wall, blocking the flow of air inwardly through the lateral ports 37, and the neck 36 reaches the plane of the discharge openings 28, breaking the pressure behind the piston 20 as compressed air is discharged into the surrounding atmosphere through the vent 29, whereupon repetition of the cycle is begun by rearward pressure of the inrushing air exteriorly of the piston as hereinbefore described.

When an operation has been concluded, the operator simply withdraws pressure from the control button 74, causing the tool's various contained springs to exert the required back pressure to close the intake valve 59 and render the indexing pin 81 yieldable, thus instantly and automatically releasing the head 14 for rotation, interchange of tool elements, or other safe and convenient manipulation.

If the head 14 is provided with additional spaced notches similar to the notches 37 and 38 at any desired points intermediate of the latter, the working head may be indexed in a number of other angular working positions within the range hereinabove described. Furthermore, the angle at which the tool or other contact element is set in the rotatable head 14 could be modified so as to arrange for presentation of the working tool at different angles than the range herein illustrated, which showing includes only the two positions most generally used in operations of the character herein discussed.

It will also be understood that the device herein illustrated is merely a representative exemplar for a large variety of pneumatic, hydraulic, and other forms of device in which the same principles could be readily employed, and it will furthermore be evident that certain of the novel features of the present disclosure could be deleted without detracting in any way from the novel character of the remaining structure, especially in devices wherein the deleted matter would be wholly unnecessary for satisfactory operation of the de-

vice for any given purpose or by reason of the use of an actuating force other than that herein disclosed. For example, where electric current is the means of operating the device, the novel valve and channel means need not be incorporated, yet the novel combination including the locking means for the indexing system would still be present and equally advantageous, and the single manually operated control button could be used for making and breaking an electric circuit with but a very slight and perfectly obvious modification of the handle portion of the device to substitute for the valve-control mechanism of the present showing. It will be just as evident that the pivot means for mounting the swivel head of the device could be a ball-and-socket joint or other acceptable expedient in substitution for the novel joint herein illustrated, the dual-purpose single control system being usable with practically any form of swivel joint employed in mounting the rotatable operating head.

I claim as my invention:

1. In a portable hand tool, the combination of an elongated base, an air channel traversing the interior of the base, an intake for said air channel, a swivel head connected to one end of the base, a pneumatic tool actuating mechanism positioned in said head, said mechanism including an air exhaust orifice, deflector means surrounding said orifice for directing flow of the exhaust air on a course in the direction of the working movement of said actuating mechanism, and channel means in said head communicating with said actuating mechanism and with the air channel located in the base.

2. In a portable hand tool, the combination of an elongated base, an air channel traversing the interior of the base, an intake for said air channel, a swivel head connected to one end of the base, a pneumatic tool actuating mechanism positioned in said head, channel means in said head communicating with said actuating mechanism and with the air channel located in the base, an indexing mechanism for interrupting rotation of the head at predetermined working positions, valve means in the base for controlling the flow of air through said air channels, means for locking said indexing mechanism in indexed position while the valve remains in open position, and a single unitary control element for manually actuating both the valve and the said locking means simultaneously, and for simultaneously closing the valve and unlocking the indexing mechanism.

3. In a portable hand tool, the combination of an elongated handle having an inclined integral rigid forward extension, an air channel traversing the interior of the handle, an intake for said air channel, a swivel head connected to said extension and rotatable on an axis at right angles to the longitudinal plane of said extension, a pneumatic tool actuating mechanism obliquely positioned in said head, channel means in said head communicating with the tool actuating mechanism and with the air channel located in the handle, and an indexing mechanism between the handle and the head for interrupting rotation of the head in any predetermined working position.

4. In a portable hand tool, the combination of an elongated handle having an inclined integral rigid forward extension, an air channel traversing the interior of the handle, an intake for said air channel, a head connected to said extension and rotatable on an axis at right angles to the longitudinal plane of said extension, a pneumatic tool

actuating mechanism obliquely positioned in said head, channel means in said head communicating with the tool actuating mechanism and with the air channel located in the handle, and an indexing mechanism between the handle and the head for interrupting rotation of the head in any predetermined working position and securely maintaining a rigid unitary relationship between the handle and the head while the tool is operative in said position.

5. In a portable tool assembly, the combination of an elongated handle, a pneumatic tool carrying head rotatably mounted at the working end of said handle, the mounting of said tool in said head being such that rotation of said head will direct said tool into a plurality of angular working positions in respect to said handle, an air supply system for said tool, a valve for controlling flow through said air supply system, and integral means for instantaneously and automatically establishing a locking connection between said handle and said tool carrying head upon opening said valve and automatically maintaining said locking connection throughout the period of flow

20 through said valve to prevent rotation of said head while said tool is in operation, said locking means being adapted for automatic and instantaneous disengagement to free said head for further rotation upon closing of said air supply valve.

30 6. In a portable power tool assembly, the combination of an elongated handle, a power-driven tool carrying head rotatably mounted at the working end of said handle, the mounting of said tool in said head being such that rotation of said head will direct said tool into a plurality of angular working positions in respect to said handle, a power supply system for said tool, means for controlling flow of power through said supply system, and integral means for establishing a locking 40 connection between said handle and said tool carrying head to prevent rotation of the latter while said tool assembly is in operation, said locking connection being automatically set upon starting of power flow to said tool and being automatically releasable for instant freeing of said head for further rotatable motion upon cessation of said power flow.

7. In a portable power tool assembly, the combination of an elongated handle, a swivel head 50 connected to one end of the handle, a power-actuated tool positioned in said head, an indexing mechanism for interrupting rotation of the head at predetermined working positions, means for controlling the power flow to said tool, means for locking said indexing mechanism in indexed position during the flow of power to said tool, and a single unitary control element for manually actuating both the power flow control means and the said locking means simultaneously, and for 60 simultaneously checking the power flow and unlocking the indexing mechanism.

8. In a portable hand tool, the combination of a handle having an integral rigid forward extension, said extension having an inclined face, 65 a fluid conducting channel carried by the handle, an intake for said fluid conducting channel, a swivel head connected to said inclined face and rotatable on an axis at right angles to the plane of said inclined face, a fluid actuated tool mechanism obliquely positioned in said head, channel means in said head communicating with the tool actuating mechanism and with the fluid conducting channel carried by the handle, and an indexing mechanism between the handle and the

head for interrupting rotation of the head in any predetermined working position.

9. A portable hand tool comprising in combination: a handle element, a swivel head rotatably mounted at one end of said handle element, a fluid-actuated mechanism adapted for holding and operating a tool element fixedly connected to and projecting outward from said swivel head, the said tool operating mechanism being so positioned on said swivel head that swiveling of said head will cause the tool held thereby to swing arcuately along a predetermined course in which said tool is capable of becoming disposed in a plurality of working positions by projecting in various angular directions in respect to the longitudinal axis of said handle element, indexing means for automatically interrupting rotation of said head when said tool has reached a desired working position along said course, said handle element carrying a fluid conducting channel having an inlet orifice adapted to be connected to a pressure fluid supply and an outlet orifice in juxtaposition with said swivel head and adapted to discharge into said head the fluid conducted through said channel, and additional channel means in said head adapted for receiving the fluid discharged from said outlet orifice and conducting said fluid into said tool operating mechanism while said tool is disposed in any of its predetermined working positions.

10. A portable hand tool comprising in combination: a handle element, a swivel head rotatably mounted at one end of said handle element, a fluid-actuated mechanism adapted for holding and operating a tool element fixedly connected to and projecting outward from said swivel head, the said tool operating mechanism being so positioned on said swivel head that swiveling of said head will cause the tool held thereby to swing arcuately along a predetermined course in which said tool is capable of becoming disposed in a plurality of working positions by projecting in various angular directions in respect to the longitudinal axis of said handle element, indexing means for automatically interrupting rotation of said head when said tool has reached a desired working position along said course, said handle element carrying a fluid conducting channel having an inlet orifice adapted to be connected to a pressure fluid supply and an outlet orifice in juxtaposition with said swivel head and adapted to discharge into said head the fluid conducted through said channel, and additional channel means in said head adapted for receiving the fluid discharged from said outlet orifice and conducting said fluid into said tool operating mechanism while said tool is disposed in any of its predetermined working positions, said additional channel means comprising a centrally disposed fluid channel communicating with said tool operating mechanism and a plurality of spaced fluid receiving orifices adapted to register with the discharge orifice of the handle's fluid conducting channel as the head is rotated, said fluid receiving orifices being spaced about the periphery of said head and being in communication with said centrally disposed fluid channel and capable of leading fluid into said tool mechanism while said mechanism is disposed in any of its various working positions.

11. In a portable hand tool, the combination of a handle having an inclined integral rigid

forward extension, a fluid passage traversing the interior of the handle, said passage having an intake orifice, a swivel head connected to said extension and capable of free movement over a predetermined course, a fluid-actuated tool mechanism fixedly connected to said head and adapted to drive a tool element, the positioning of said tool mechanism on said head being such that movement of said head will direct the said tool element into a plurality of angular working positions with respect to said handle, a fluid outlet orifice in said handle extension adapted to discharge fluid passing through the aforesaid fluid passage, a fluid passage in said head having a fluid receiving orifice adapted to register with and receive fluid discharged by the handle's said outlet orifice and adapted to supply operating fluid under proper pressure to said tool mechanism, and an indexing system formed of co-operating means located at the junction of said handle and said head for interrupting movement of the head in any predetermined working position by snap-in action automatically establishing and securely maintaining the desired operative angular setting of said tool in any of said working positions and simultaneously resulting in a rigid unitary relationship between the handle and the head while the tool is operative in any of said positions.

12. In a portable hand tool, the combination of a handle having an inclined integral rigid forward extension, a fluid passage traversing the interior of the handle, said passage having an intake orifice, a swivel head connected to said extension and capable of free movement over a predetermined course, a fluid-actuated tool driving mechanism fixedly connected to said head and adapted to drive a tool element, the connection between said mechanism and said head being such that movement of said head will direct the tool element into a plurality of angular working positions with respect to said handle, a fluid outlet orifice in said handle extension adapted to discharge fluid under pressure from said handle passage, a fluid passage in said head having a plurality of spaced fluid receiving orifices arranged so as to separately move into registration with and receive discharged fluid under pressure from the handle's discharge orifice and in turn lead said fluid to said tool driving mechanism for the purpose of actuating said tool element while the latter is disposed at any of its said angular working positions.
